(57) **CLAIM**

The ornamental design for a heart necklace, as shown and described.

DESCRIPTION

FIG. 1 is a first perspective view of a heart necklace showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 3;

FIG. 10 is an enlarged view of the selected portion 10 in FIG. 3;

FIG. 11 is an enlarged view of the selected portion 11 in FIG. 3; and,

FIG. 12 is an enlarged view of the selected portion 12 in FIG. 3.

The dot-dash broken lines surrounding the enlarged views are for annotative purposes only and form no part thereof. The faded-out portions represent parts of the article that form no part of the claim.

1 Claim, 12 Drawing Sheets
